(57) **CLAIM**

The ornamental design for a rock shield for towed vehicle, as shown and described.

DESCRIPTION

FIG. 1 is a perspective view of the rock shield for towed vehicle showing my new design, the dashed line showing of the vehicle and the towing mechanism being shown for illustration purposes only and does not form a part of the invention;

FIG. 2 is a front elevational view of the rock shield;

FIG. 3 is a top plan view thereof;

FIG. 4 is a right side elevational view thereof, the left side elevational view being identical thereto;

FIG. 5 is a rear elevational view thereof; and,

FIG. 6 is a bottom plan view thereof.
